UNITED STATES PATENT OFFICE.

JEREMIAH B. BOWMAN AND ALVIN S. BOWMAN, OF PALMYRA,
PENNSYLVANIA.

DESIGN FOR A KNIFE-BLADE.

SPECIFICATION forming part of Design No. 28,311, dated February 22, 1898.

Application filed May 5, 1897. Serial No. 635,265. Term of patent 14 years.

To all whom it may concern:

Be it known that we, JEREMIAH B. BOWMAN and ALVIN S. BOWMAN, citizens of the United States, residing at Palmyra, in the county of Lebanon and State of Pennsylvania, have invented a new and original Design for a Knife-Blade, of which the following is a specification.

This invention relates to a new and original design for a knife-blade; and it has for its object to provide a design of this character that shall be both useful and ornamental.

The leading feature of the design resides in a knife-blade having at a point centrally between its ends a straight flat portion with parallel side edges, and opposite duplicate reversely-curved portions extending in opposite directions from the central straight portion and tapering to a point.

In the drawing the figure is a perspective view of a knife-blade embodying the herein-described design.

Referring particularly to the drawing, the numeral 1 designates a knife-blade having at a point between its ends a central straight flat portion 2 with parallel side edges 3. From opposite sides of the central straight flat portion 2 of the knife-blade are extended the opposite duplicate reversely-curved portions 4, which taper to a point 5 and are beveled at one edge, as at 6.

What we claim is—

The design for a knife-blade herein shown and described.

In testimony that we claim the foregoing as our own we have hereto affixed our signatures in the presence of two witnesses.

JEREMIAH B. BOWMAN.
ALVIN S. BOWMAN.
